(57) **CLAIM**

The ornamental design for a hair roller retention device, as shown and described.

DESCRIPTION

FIG. 1 is a perspective view of a hair roller retention device showing my new design as when securing a hair roller to the head of a person;

FIG. 2 is a top view thereof;

FIG. 3 is a front view thereof;

FIG. 4 is a right-side view thereof;

FIG. 5 is a back view thereof; and,

FIG. 6 is a bottom view thereof.

Dashed lines indicate material disclaimed from the invention and are for purposes of illustration only.
